UNITED STATES PATENT OFFICE.

WILLIAM DOUGLAS WOODWARD, OF WEST CHAZY, NEW YORK, ASSIGNOR OF ONE-HALF
TO CHARLES A. LEFEE, OF PLATTSBURG, NEW YORK.

AUTOMATIC SWITCH.

Application filed June 20, 1923. Serial No. 646,632.

To all whom it may concern:

Be it known that I, WILLIAM DOUGLAS WOODWARD, a citizen of the United States, residing at West Chazy, in the county of Clinton and State of New York, have invented a new and useful Automatic Switch, of which the following is a specification.

This invention aims to provide a means whereby a switch may be set for a siding, by an approaching train or vehicle, the switch being automatically restored to main line position, after the train has entered the siding.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings:

Figure 1 shows in top plan, a switch mechanism constructed in accordance with the invention; Figure 2 is a perspective view disclosing one of the switch members; Figure 3 is a perspective view disclosing the other of the switch members; Figure 4 is a side elevation of the actuating bar; Figure 5 is a sectional view taken approximately on the line 5—5 of Figure 1; Figure 6 is a transverse section taken through the support or casing; Figure 7 is a longitudinal section taken through the casing, the line 6—6 of Figure 7 indicating the cutting plane on which Figure 6 is taken; Figure 8 is a cross section taken on the line 8—8 of Figure 1; Figure 9 is a similar cross section, showing a modification.

The numeral 1 designates ties, carrying a main track rail 2 and a main track rail 3, one of the siding rails being marked by the numeral 4, and the other of the siding rails being designated by the numeral 5. A rail of peculiar construction constitutes a continuation of the rail 5, and, as shown in Figure 8, is made up of angle members 6, the rail under consideration being designated generally by the numeral 7.

The numeral 8 designates, generally, a switch member comprising an arm 9 and a head 10, the arm 9 being pivoted at 11 to the inside of the rail 2 and so constituted that when the arm 10 is raised, as herein-after described, the head 10 will bridge the space between the main line rail 2 and the siding rail 3, thereby deflecting the wheel of a car from the rail 2 to the rail 4, assuming that the train is moving in the direction indicated by the arrow A in Figure 1.

The numeral 12 designates a switch member made up of an arm 14 and a head 15, the arm 14 being pivoted at 16 to the members 6 of the rail 7 and lying between the said members. The head 15 is so constructed that when it is raised, it will bridge a space 17 existing in the rail 3, the rail 3 having an off-set portion 18 disposed adjacent to said space and aligned with the rail 7. When the head 15, however, is lowered, then the wheel of a passing car or engine, traversing the rail 3 in the direction of the arrow A in Figure 1 will move from the rail 3 upon the off-set 18 and pass thence upon the rail 7.

The numeral 19 designates a box-like support having a lid 20 which is hingedly mounted, as shown at 21 and is held closed by any suitable means indicated at 22. A shaft 23 extends longitudinally of the support 19 and is journaled in bearings 24 in the support, the shaft having a crank 25, which, as shown in Figure 7 coacts with the head 10 of the switch member 8. The shaft 23 is supplied with a crank 26, adapted to coact with the head 15 of the switch member 12. The cranks 25 and 26 are so set that when the crank 26 raises the head 15 of the switch member 12 the crank 25 will permit the head 10 of the switch member 8 to move downwardly and vice-versa. A weight 27 is mounted on the shaft 23 and is located within the support 19, the cranks 25 and 26 being so disposed with respect to the weight 27 that the weight tends to maintain the switch members 8 and 12 set for the main track. In its lower edge, the weight 27 has seats 28 adapted to be engaged by spring pawls 29, mounted on the bottom of the support 19, and operating to hold the weight yieldingly but securely in the depending position delineated in Figure 6.

A means is provided for rotating the shaft 23, and with this end in view, the shaft has

cranks 30, whereon operating members or bars 31 are pivoted at one end. Each operating member 31 is mounted at its opposite end on a swinging support 32, mounted to rock in bearings 33 carried by one of the ties 1, the operating members 31 being beveled, each, at one end, as shown at 4, so that a car-carried means, of any desired sort described, may ride readily on the operating members 2. It may be desirable at times to throw the switch by hand, and, with this consideration in mind, the shaft 23 carries, as shown in Figure 7, a beveled pinion 35, meshing with a beveled pinion 36, carried by a shaft 37, the shaft being journaled in a switch stand 38, mounted on certain of the ties 1, or otherwise disposed. The numeral 39 designates any suitable means for rotating the shaft 37 by hand. In order that the hand-operated mechanism may not interfere with the automatic throwing of the switch, a portion of the beveled pinion 36 on the shaft 37 is smooth, as designated by the numeral 40.

It is obvious that when the head 10 of the switch member 8 is lowered, and when the head 15 of the switch member 12 is raised, the continuity of the main track will be maintained. A vehicle, approaching the switch in the direction of the arrow A on the main track, depresses one of the operating members 31, rotation is imparted to the shaft 23, the crank 25 raises the head 10 of the switch member 8 and lowers the head 15 of the switch member 12, and, then, the vehicle is shunted into the siding. The switch remains set for the siding until the last wheel of the last vehicle in the train, entering the siding, has moved off the arm 14 of the switch member 12, whereupon the weight 27 will react on the shaft 23, restoring the heads 10 and 15 of the switch members to main line position, the spring pawls 29 coacting with the seats of the weight 27 to prevent the shaft 23 from rocking, sav-

ing when the shaft 23 is rotated through the instrumentality of one of the operating members 31.

Although in Figure 8 the arm 14 of the switch member 12 is shown as located between the constituent parts 6 of the siding rail 7, the structure shown in Figure 9 may be used if desired, the member 14 being replaced by a channel 41, inverted slidably over the flange 42 of a rail including a base 43.

What is claimed is:—

1. The combination with main and siding rails, of vertically swinging switch members cooperating with the main and siding rails, a shaft mounted for rocking movement and provided with angularly disposed cranks coacting with the switch members, a weight carried by the shaft, and an operating member mounted for longitudinal movement and for swinging movement, the shaft having a crank whereon the operating member is pivoted and means for supporting the operating member for movement.

2. The combination with main and siding rails, of vertically swinging switch members cooperating with the main and siding rails, a shaft mounted for rocking movement and provided with angularly disposed cranks coacting with the switch members, a weight carried by the shaft, mechanism for actuating the shaft, said mechanism being so constructed as to be operated by a passing car, and mechanism for holding the shaft yieldingly against rocking movement, said mechanism embodying a spring pawl, engaging the weight releasably.

In testimony that I claim the foregoing as my own, I have hereto affixed my signature in the presence of two witnesses.

WILLIAM DOUGLAS WOODWARD.
